(57) **CLAIM**

We claim the ornamental design for a wound therapy training device, as shown and described.

DESCRIPTION

FIG. 1 is a top perspective view of an embodiment of the claimed design;

FIG. 2 is a bottom perspective view thereof;

FIG. 3 is a top view thereof;

FIG. 4 is a bottom side view thereof;

FIG. 5 is a right side view thereof;

FIG. 6 is a left view thereof; and

FIG. 7 is a front view thereof;

FIG. 8 is a rear view thereof;

FIG. 9 is a cross-sectional view thereof along line 9-9 shown on FIG. 1;

FIG. 10 is a front perspective view thereof in one possible usage environment;

FIG. 11 is a top perspective view of another embodiment of the claimed design;

FIG. 12 is a bottom perspective view thereof;

FIG. 13 is a top view thereof;

FIG. 14 is a bottom side view thereof;

FIG. 15 is a right side view thereof;

FIG. 16 is a left view thereof; and

FIG. 17 is a front view thereof;

FIG. 18 is a rear view thereof;

FIG. 19 is a cross-sectional view thereof along line 19-19 shown on FIG. 11; and,

FIG. 20 is a front perspective view thereof in one possible usage environment.

The broken lines in the FIG. 10 and FIG. 20 depict environment and form no part of the claim.
